United States Patent [19]

Lal et al.

[11] Patent Number: Des. 319,506

[45] Date of Patent: ** Aug. 27, 1991

[54] I.V. FLOW REGULATOR

[75] Inventors: Birendra K. Lal, Glendale Heights; Steven K. Neuenfeldt, Vernon Hills; Mark A. Hoekwater, Mundelein, all of Ill.

[73] Assignee: Baxter International Inc., Deerfield, Ill.

[**] Term: 14 Years

[21] Appl. No.: 353,375

[22] Filed: May 17, 1989

[52] U.S. Cl. D24/129

[58] Field of Search D24/53, 51; 604/246, 604/244, 250, 252, 251, 249, 247, 298, 248, 126, 32, 33, 905; 137/501, 445, 505, 504, 503; 251/205, 208, 209; 138/37, 46

CLAIM

The ornamental design for an I.V. flow regulator, as shown and described.

DESCRIPTION

FIG. 1 is a top perspective view of an I.V. flow regulator, showing our new design;

FIG. 2 is a top plan view thereof;

FIG. 3 is a side perspective view thereof;

FIG. 4 is a bottom plan view thereof;

FIG. 5 is a front side elevational view thereof; and,

FIG. 6 is a back side elevational view thereof.

FIG. 1

FIG. 2

FIG. 3

FIG. 4

FIG. 5

FIG. 6
